UNITED STATES PATENT OFFICE.

HERMANN HILL, OF SAVANNAH, GEORGIA, ASSIGNOR, BY DIRECT AND MESNE ASSIGNMENTS, TO PRENDERGAST ELECTRIC TYPEWRITER COMPANY, A CORPORATION OF MAINE.

CARRIAGE FOR TYPE-WRITING MACHINES.

No. 835,828.

Specification of Letters Patent.

Patented Nov. 13, 1906.

Application filed April 14, 1902. Serial No. 102,801.

To all whom it may concern:

Be it known that I, HERMANN HILL, a subject of the Emperor of Austria, and a resident of Savannah, Chatham county, State of Georgia, have invented certain new and useful Improvements in Carriages for Type-Writing Machines, of which the following is a specification.

My invention relates to carriage-feeding mechanism for type-writing machines; and my object is to provide a carriage-feeding mechanism which shall positively feed the carriage the required distance upon the movement of any key-lever or the spacing-lever and which shall be applicable not only to motor-actuated machines, such as electrically-operated machines, but to any machine in which the movement of the key-levers and spacing-lever controls a movable element of the machine for transmitting motion to the feeding devices.

My object also is to provide a simple device on the carriage whereby different widths of paper may be used with the least number of parts and the simplest mode of operation.

With these objects in view my invention consists of the novel construction and details thereof, as hereinafter described with reference to the accompanying drawings and more particularly pointed out in the claims.

In the drawings, Figure 1 is a vertical section of a carriage with the connected parts according to my invention and so much of the frame of a machine as to show the application of my invention thereto. Fig. 2 is a bottom plan view. Fig. 3 is an end view of the carriage. Figs. 4, 5, and 6 are enlarged details of the carriage-feeding devices, and Fig. 7 is an enlarged detail of a preferred modification.

In the drawings, where the same characters relate to the same or corresponding parts in all the views, the carriage 1 is slidably mounted in guides 2, carried by brackets 3, fixed to the frame 4 of the machine, said carriage being preferably in the form of a U-bar, between the upper and lower flanges of which are rollers 5, mounted in suitable antifriction-bearings, the peripheries of said rolls being confined to travel in grooves in the guides 2.

Projecting from the bottom flange of the carriage 1 are two rack-bars 6 and 7, the former preferably having curved teeth adapted

to be engaged by a roll 8, yieldingly held in contact with said teeth by a spring 9, fixed to one of the guides 2, on which spring said roll is supported. The purpose of this rack-bar and its coöperating roll or pawl is to check the carriage as it is intermittently moved, so as to prevent it from being moved more than one tooth or the proper space at each operation of the carriage-feeding mechanism.

The carriage-feeding mechanism is best seen by reference to Figs. 1, 4, 5, and 6, where the rack-bar 7 is shown extending downwardly from the carriage 1, with which bar the pawl 10 is adapted to engage. The pawl 10 is in the form of a plate having a tooth formed to engage with the tooth of the rack-bar 7 and is slidably mounted in guideways in a horizontal slide 11, adapted to reciprocate in a slideway in a plate 12, fixed to the frame 4 of the machine. A pin 13 projects from the slide 11 into a slot 14 in the pawl to limit the extent of its movement. The slide 11 is held in frictional contact with its supporting-plate 12 by a frictional device consisting in the present instance of a spring 15, (see Fig. 6,) confined between a collar 16 on a stud 17 and a bearing plate or collar 18, which stud projects from the plate 11 through an elongated slot 19 in the plate 12. The pawl is so mounted in a diagonal guideway in the plate 11 that the frictional resistance between the two shall be appreciably less than that between the plate 11 and its guiding or supporting plate 12, whereby when a pull is exerted upon the pawl in a horizontal direction it will first move in its guideway, thereby causing the tooth of said pawl to advance into engagement with a tooth on the rack-bar 7, and further force in the same direction will cause both pawl and the slide 11 to move in the direction of pull, and consequently effect the movement of the carriage one tooth or the proper space. This difference in frictional resistance between the two parts reduces to a minimum the force necessary to set the pawl in position to effect the actual motion of translation of the carriage.

In order to set the pawl in the manner above noted, as by means of the movable armature of an electromagnet or other movable element of the machine, a link 20, pivoted at 21 to the pawl, connects the latter to a bell-

crank 22, fulcrumed at 23 on an extension 24 on the fixed plate 12. The short arm of said bell-crank has a pointed end 25 bearing in a recess in a lever 26, fulcrumed at 27 to 5 the fixed plate 12. This lever has an offset portion around the short arm of the bell-crank 22, from which offset portion extends a pin 28 in line with the fulcrum 27, which pin is engaged by the forked end of a lever 10, 29, fulcrumed at 30, and having its other end engaging the pin 31, carried by the armature 32 or other movable element of the machine, which is controlled by the movement of the key-levers or spacing-lever. Movement of 15 the armature upon the depression of a key throws the forward forked end of the lever 29 downward, thereby depressing the lever 26 downward, and likewise lowering the pointed end 25 of the lever 22, thereby causing 20 the link 21 to push the pawl downward in its slideway on the slide 11, and continued downward movement of the lever 26 moves the pawl and slide backward to a position for the next advance movement of the pawl. 25 The bell-crank 22 is connected to a rod 33, passing through a guiding hole or slot on the frame 4 and having a helical spring 34 at its outer end bearing against a collar on said rod and against the frame. Upon the depression 30 of the lever 26 this spring, which is under compression, is further compressed on the movement of the rod 33 by the bell-crank 22, when the latter sets the pawl, as above described, and hence the moment the key-lever is released and, in the example shown, the circuit broken and the armature returns to its inactive position the first effect of the consequent reverse movement of the lever 26—that is, upwardly—is to cause the 40 pawl to slide upwardly on the slide 11 and engage the tooth of the bar 7, as shown in Fig. 4. The spring 34 being now free to exert its full force pulls the lever 22, the pawl 10, and slide 11 horizontally the distance required to move the carriage one tooth or 45 proper space. The action of the feeding pawl or dog 10 is thus seen to embody a four-cycle motion, for when the lever 26 is depressed by the link connection between it and the armature or other movable element 50 of the machine the first motion is a diagonally-downward motion of the pawl in its guide on the plate 11, disengaging the tooth from the rack-bar 7, and the final downward motion of the lever 26 causes the pawl to 55 move with the plate 11 bodily backward into position under the next tooth of the rack 7, and while such movements are taking place the type-wheel has been brought to printing position, and the hammer then delivers its 60 blow. Then immediately upon the release of the key or breaking of the circuit the armature falls, during the first part of which falling movement of the armature the pawl is 65 pulled upwardly into engagement with the

rack 7, and the spring 34, exerting its pull upon the lever 22, positively pulls the pawl and the plate 11 horizontally forward, thereby imparting a positive feeding movement to the carriage, the latter not being connected directly with any spring or like device. Simultaneously with the completion of the return downward movement of the armature the spring 34 completes its pulling of the pawl 10 to the left, and the lever 26 is then in its normal position, where no further force can be imparted to the pawl by the spring. Near the limit of this movement the power of the spring 34 of course decreases, but the impetus given to the carriage, by reason of the 80 ease with which it is adapted to move, may tend to impart a greater extent of movement than that desired, and in order to prevent this result the roll 8 on the spring-pawl 9 slips into engagement with a tooth on the 85 bar 6, the pressure being sufficient to check the movement of the carriage due to the momentum, but not sufficient to interfere with the direct and positive movement of said carriage by the pawl 10 when the latter is under the action of the spring 34 during the necessary part of the carriage movement to shift the same a sufficient distance for the spacing, such pawl 8 holding the carriage until the next operation of the pawl 10. 95

The line-spacing devices are not shown, as they may be of any well-known type of pawl-and-ratchet mechanism, nor is it deemed necessary to show the carriage-shifting lever for returning the carriage at the completion of a line, such shifting-lever being of any known type and forming no part of my present invention. It may be noted, however, in this connection that as the normal position of the pawl 10 (see Fig. 4) would ordinarily prevent shifting the carriage to the right it is only necessary to press down upon the space-bar, thereby completing the circuit through the magnet as the carriage is shifted, whereby the first or downward movement of the dog 10 is effected by the motor and permits the shifting of the carriage. 105

In the preferred construction, a detail of which is shown in Fig. 7, I avoid the necessity of touching the space-bar or other operating part to permit shifting of the carriage, as above described, and, moreover, dispense with the spring 34 and its co-operating parts, thereby rendering the carriage freely movable to the right or left and further simplify the construction, as will appear from the following description. In this form the bell-crank lever 22^a is mounted, as before, on the fixed frame, as on the extension 24, and is connected by the link 20 to the pawl 10, but instead of using a second lever corresponding to the lever 26 in the construction shown in Figs. 1, 2, and 3 I fulcrum the bell-crank 22^a so that its arm 22^b shall be in position for engagement with the lever 29, connected to the 110

movable element—such as the armature 30. The result of this construction is that downward movement of the arm of the lever 29, connected to the bell-crank, due to the upward movement of the armature, acts directly upon the bell-crank arm 22^b, thereby causing the pawl 10 to first move upwardly from the normal position shown in Fig. 7 to engage the rack-bar, and continued movement of the lever 29 in the same direction pulls, by direct action of the movable element through its lever 29, the pawl and plate 11 forwardly, thus positively feeding the carriage the proper predetermined space. Movement of the armature in the reverse direction when the circuit is broken causes the pawl to move downwardly, disengaging it from the rack-bar, thence backwardly with the plate 11, thereby resuming its normal position for engaging the next tooth. This feeding movement of the carriage is of course effected before the impression device is operated to print. The other parts in this form are the same as hereinbefore described and operate in the same way, and in both cases it will be observed that movement of the movable element in one direction causes the pawl to move upwardly and then forwardly for the feeding motion of the carriage, while the movement of said movable element in reverse direction causes the pawl to move downwardly and then backwardly to set it for engagement with the next tooth, these motions, however, occurring in the reverse order in the two cases.

In the form shown in Figs. 1 to 6, the normal position of the pawl being in engagement with the tooth, the motion is first downwardly and then backwardly to set it for engagement with the next tooth, while in the form shown in Fig. 7 the pawl is normally out of engagement with the tooth and the motion is therefore first upwardly and thence forwardly, thereby dispensing with the need of any spring connection and with any means for holding the carriage requiring release before the carriage can be moved. The carriage is thus free to be moved to the left, as well as to the right, without requiring, as heretofore, the release of any carriage-holding device, and I therefore define the carriage in this preferred form of my invention as "freely movable."

It is obvious that the carriage-feeding devices may be applied to any machine wherein a movable element is controlled by the depression of any key-lever, such movable element being connected to the carriage-feed devices through the medium of a lever, such as the lever 29.

The platen or paper-cylinder 35 is mounted in end frames 36, the spindle 37 of said cylinder having a gear 37 meshing with a pinion 38 on a shaft 40 in spring-bearings 39, whereby positive motion may be imparted

to the cylinder when it is desired to turn the same or by the hand-wheel 40 on the spindle 37. On the shaft 40 I mount frictional contact-rolls 41 of yielding material distributed throughout the length of the cylinder or in one piece, as desired. By this means sheets of different widths may be used without involving any particular adjustment of parts, as is needed ordinarily in machines of this type. 75

I have indicated conventionally a circuit including the magnet, in which a suitable circuit-closing device is indicated at 42, the battery being indicated at B, and the wires leading therefrom to the magnet and to the circuit-closing device, the circuit being completed in a convenient way through the conducting-frame of the machine.

I claim as my invention—

1. In a type-writing machine, the combination with the operating mechanism of the machine, of a carriage having a rack-bar thereon, a feed-pawl slidably carried on the frame of the machine, a movable element forming part of the operating mechanism of the machine, connections between said feed-pawl and said movable element, whereby movement of the movable element in one direction will impart distinct upward and forward movements to said feed-pawl to feed the carriage, and reverse movement of said movable element will impart a downward and a backward movement to the feed-pawl to set the pawl for engagement with the next tooth of the rack-bar, substantially as described. 85 90 95 100

2. In a type-writing machine, the combination with a carriage having a rack-bar thereon, a plate slidably mounted on the frame of the machine, a feed-pawl slidably mounted in a guide on said plate, a movable element of the machine, connections between the pawl and the movable element, whereby motion of the movable element in one direction will cause the pawl to move upwardly in its guide and then forwardly with the plate, and reverse motion of said movable element will cause said pawl to first slide downwardly in its guide and then push the pawl and plate backwardly, substantially as described. 105 110 115

3. In a type-writing machine, the combination with a carriage having a rack-bar thereon, a plate slidably supported on the fixed frame, a pawl slidably mounted in a guide on said plate, said plate being held in frictional contact with its support greater than the frictional contact between the pawl and plate, a movable element of the machine, a lever fulcrumed on the fixed frame and connected to the movable element, and a link connecting the pawl with the lever, substantially as described. 120 125

4. In a type-writing machine, the combination with the operating mechanism of the machine, of a carriage slidably mounted 130

- upon the frame of the machine, of a rack-bar on said carriage, a feed-pawl slidably carried on the frame of the machine, positively-acting means controlled by the operating mechanism of the machine for moving the pawl out of engagement with one tooth on the rack into position for another tooth and then moving said pawl into engagement with said latter tooth for positively feeding the carriage forward, substantially as described.
5. In a type-writing machine, the combination with a carriage slidably mounted upon the frame of the machine, of a rack-bar on said carriage, a plate slidably mounted on the frame, a feed-pawl slidably mounted on the plate, and means for imparting an upward motion of the pawl on the plate to engage another tooth and then a forward motion of the pawl and plate to positively feed 15 the carriage, substantially as described.
10. The combination with the carriage having two racks thereon, a feed-pawl adapted to engage one rack for positively feeding the carriage forward, a second pawl yieldingly mounted on the fixed structure and having a roll adapted to engage the second rack and check the carriage, substantially as described.
15. In a type-writing machine, the combination with a carriage slidably mounted on the frame of the machine, of a rack on said carriage, a plate slidably mounted on the frame of the machine, a pawl slidably mounted in an inclined guide thereon, means for moving the pawl upwardly in its guide to engage another tooth of the rack and then forwardly with the plate to positively feed 20 the carriage, substantially as described.
20. The combination with the carriage having two racks thereon, a feed-pawl adapted to engage one rack for positively feeding the carriage forward, a second pawl yieldingly mounted on the fixed structure and having a roll adapted to engage the second rack and check the carriage, substantially as described.
25. In a type-writing machine, the combination with a carriage slidably mounted on the frame of the machine, of a rack on said carriage, a plate slidably mounted on the frame, a pawl slidably mounted in an inclined guide on said plate, a lever fulcrumed on the fixed frame, connections between said lever and an operating part of the machine, whereby motion imparted to the lever in one 30 direction will impart an upward and forward motion to the pawl, and, in the other direction, a downward and backward motion, substantially as described.
30. In a type-writing machine, the combination with carriage slidably mounted on the frame of the machine, of a rack on said carriage, a plate slidably mounted on the fixed frame, a pawl slidably mounted in an inclined guide on said plate, a bell-crank fulcrumed on the frame, a link connecting one 35 arm of the bell-crank with the pawl, connections between an operating part of the machine and the other arm of the bell-crank, whereby motion of said lever in one direction imparts an upward and forward motion to the pawl and motion in the other direction a downward and backward thereto, substantially as described.
35. In a type-writing machine, the combination of the operating mechanism of the machine, of a carriage slidably mounted upon the frame of the machine, of a rack-bar on said carriage, a feed-pawl slidably carried on the frame of the machine, and positively-acting means controlled by the operating 40 mechanism of the machine for moving the pawl out of engagement with one tooth on the rack into position for another tooth and then moving said pawl into engagement with said latter tooth for positively feeding the carriage forward, substantially as described.
40. The combination with the carriage having two racks thereon, a feed-pawl adapted to engage one rack for positively feeding the carriage forward, a second pawl yieldingly mounted on the fixed structure and having a roll adapted to engage the second rack and check the carriage, substantially as described.
45. In a type-writing machine, the combination with the carriage freely movable to the right or left, of a pawl slidably mounted upon the frame of the machine for positively feeding the carriage forward, and positive connections between the pawl and the operating mechanism of the machine for causing the pawl to engage the carriage and positively move the same, substantially as described.
50. In testimony whereof I have signed my name to this specification in the presence of two subscribing witnesses.
